UNITED STATES PATENT OFFICE.

JOHN GOSLING, OF NEW YORK, N. Y.

WINDOW-SEAT.

SPECIFICATION forming part of Letters Patent No. 608,366, dated August 2, 1898.

Application filed April 12, 1898. Serial No. 677,302. (No model.)

To all whom it may concern:

Be it known that I, JOHN GOSLING, a citizen of the United States, and a resident of New York, in the county of New York and State of New York, have invented certain new and useful Improvements in Window-Seats, of which the following is a specification, reference being had to the accompanying drawings, forming part of the same, in

10 which—

Figure 1 is a perspective view of one form of my device, represented as in place in a window, only portions of which are shown. Fig. 2 is a similar view of such device in the 15 position it occupies when it is being put in place or being removed, but is almost in place. Fig. 3 is a view in perspective of said device when closed up and ready for transportation. Fig. 4 is a sectional view of the same on lines 20 4 4 of Fig. 3. Fig. 5 is a sectional view of part of a closed seat, slightly modified. Fig. 6 shows the seat of Fig. 5 opened. Fig. 7 represents a modification in which the seat is fixedly pivoted to the back and hinged intermediate that and the frame. Fig. 8 is a sectional view of another modification, shown 25 open; and Fig. 9, a similar view of said last-named device as it appears when being closed.

This invention relates to window-seats; and 30 it consists in the devices and combinations of devices hereinafter described and claimed.

My intent in devising this seat has been to produce one that could be readily put in place or removed, would be entirely safe when in 35 place, and more especially one that could not be used without first being so arranged that it would be safe, and said latter feature is one of the main novelties of this apparatus. I have made it a folding device that it might 40 be easily shifted from place and stored in small space when not in use, and in making it so I have still so combined the parts as to retain the safety features.

F is the main frame, usually composed of 45 uprights U and cross-bars C of such a length as to extend below the sill of a window and above the line of the meeting-rail of the sash and preferably such a width as will be within that of the window-opening. To this frame 50 I pivot a back B, composed of uprights b b'

and cross-bars c c', or it might be one broad piece, but as arranged is lighter and stronger. The connecting-rods R are preferably pivoted to the frame at or below the level of the inner end of the seat proper and to the back 55 at points well above such level in order that when one has seated himself in the device he may draw the sash well down in order to clean the panes, (which he could not do if the inner ends were pivoted much above said level,) 60 and that at the same time the back may be well supported, which it would not be if the rods were not attached well above the level of their inner pivots. A cross-bar C², preferably rounded, is arranged to come just at 65 or above the inner edge of the sill, and brackets A may also be provided to extend over the sill and hold the frame from slipping down, or said cross-bar C² may be arranged to accomplish that purpose, in which event it 70 should be, as shown, secured to the outer side of the frame. This also makes it easier to sit well out on the seat.

S, the seat proper, is pivoted, preferably, to the inner sides of frame F and made of 75 such width that it may when turned up lie within such frame, and thus be more out of the way. As shown, it consists of a suitably-shaped board S', held by two rods R', and to hold the seat and back firmly in position I 80 provide on the inner side of each upright b b' lugs L, made of a base-piece l, adapted to rest upon the outer edge of the sill, of such a height as the usual difference in level between the inner and outer edges of the sill, 85 (that the seat may be level when in position,) also adapted to have the board S' rest upon their upper faces, and with holding-pieces h, tapered at the top, extending upward in line with the uprights b b' and adapted to engage 90 in notches n, cut in the side edges of board S', and thus hold the back and seat together against longitudinal movement to or from the windows.

The result is plain. First the device may 95 be shut up into small compass, as shown in Fig. 3. The seat and its rods lie in between the uprights U, and the back, controlled by rods R and always in an upright position, comes up flush with said uprights, when a 100

hook and eye *j k* readily secure and hold them in their closed position. When to be used, the window is opened, the frame adjusted, with brackets *A* on the sill and the uprights against the sash, and the hook is disengaged. The back and seat at once fall out in position, the notches *n* engage the holding-pieces *h*, and the board rests upon the lugs *l*, and the device is ready for use. To insure that the lower ends of uprights *b b'* do not swing out too far, chains or cords *d* may be employed. It will be noticed that the back does not need to be turned up in position after the seat is placed, also that as the seat unopened closes the space through which the body of the person about to use the apparatus must pass it must be pushed out to permit such passage. The back must fall out, so that no forgetfulness on the part of the operator can result in his getting out of the window before the parts are in proper and safe position. If either the seat or back were to be adjusted after the rods swing out, one might first get out and an accident occur, because of the neglect to first arrange all the parts as they should be. The pivoting of the back, as described, is a main feature in this connection.

As a further insurance I may add an engaging device, such as *E*, which is an arm extending inward from the upright bar of the back and having an inwardly-reaching finger, preferably provided with a roller, which lies over and against the upper side of board *S'* or its connecting-rod, as seen in Fig. 5. Then when the back or the seat is pushed outward this engaging device will insure the proper relative movement of the other members of the combination, drawing the seat out if the back be pushed or holding the back and seat close together if the seat be pushed till such time as notches *n* and holding-pieces *h* properly engage each other, the turning of the seat being readily permitted if the pivot of arm *E* be located as high as the thickness of seat *S'* above its intended resting-place or a little higher to permit easy engagement of the notches and lugs, as shown in Fig. 6. I may also secure this result by pivoting the outer end of the seat fixedly to the back, as shown in Fig. 7, in which event I joint and hinge the seat to permit the ready and easy closing of the device, the long part when closed resting between the uprights *U* and the short part between the rails *b b'*, or, if joints are objectionable, I can arrange for the folding by permitting the pivots *P* to run in grooves *g* in the rails *b b'*, as seen in Figs. 8 and 9, in which event I prefer to locate the point of pivot below the level of the seat in order that when folded up it may still lie within the line of the frame. A snap-catch *q* would also best be provided to insure that the rods *R'* may assist in holding the seat in position if the sill should be short. Such a catch might be also applied to the

other forms of devices at the lug of Fig. 1 or at the hinge of Fig. 7.

What I claim as my invention, and desire to secure by Letters Patent, is—

1. The combination in a window-seat of a frame adapted to reach across a window-opening and be sustained therein, an upright back pivoted thereto and provided with an engaging device and a seat also pivoted to said frame and provided with an engaging device, adapted to engage the device of the back, all substantially as set forth.

2. The combination in a window-seat of a frame adapted to reach across a window-opening and be sustained therein, a back pivoted thereto by rods the inner ends of which are secured to the frame at or near the sill-level and the outer ends of which are secured to said back at points above said inner points of pivoting and a seat arranged substantially as set forth, all substantially as set forth.

3. In a window-seat, a frame adapted to reach across a window-opening, a support secured to said frame and adapted to rest upon the sill, an upright back, rods pivoted to said back and to said frame, a seat pivoted to swing inside the back and within the frame, an engaging device upon the seat, an engaging device upon the back adapted to be engaged by that upon the seat, and a seat-support secured to the back, all combined substantially as set forth.

4. In a window-seat, a frame adapted to reach across a window-opening, a support secured to said frame and adapted to rest upon the sill, an upright back, rods pivoted to said back and to said frame, a seat pivoted to swing inside the back and within the frame, an engaging device upon the seat, an engaging device upon the back adapted to be engaged by that upon the seat, and a seat-support secured to the back, and a controlling-finger adapted to insure proper relative movement of the back and seat, all combined substantially as set forth.

5. In a window-seat, a frame adapted to reach across a window-opening, a support secured to said frame and adapted to rest upon the sill, an upright back, rods pivoted to said back and to said frame, a seat pivoted to swing inside the back and within the frame, notches in the seat and lugs upon the back adapted to engage each other, and a seat-support secured to the back, all combined substantially as set forth.

6. In a window-seat, a frame adapted to reach across a window-opening, a support secured to said frame and adapted to rest upon the sill, an upright back, rods pivoted to said back and to said frame, the inner pivots being below the level of the outer pivots as described, a seat pivoted to swing inside the back and within the frame, an engaging device upon the seat, an engaging device upon the back adapted to be engaged by that upon the seat,

and a seat-support secured to the back, all combined substantially as set forth.

7. The combination in a window-seat of a frame adapted to reach across a window-opening and be sustained therein, an upright back pivoted thereto and provided with an engaging device and a seat also pivoted to said frame and provided with an engaging device, adapted to engage the device of the back, and

a catch adapted to hold them in engagement, to all substantially as set forth.

Signed at New York city, in the county of New York and State of New York, this 8th day of April, A. D. 1898.

JOHN GOSLING.
